United States Patent Office

Des. 198,669

Patented July 21, 1964

198,669

DOOR HANDLE

Donald S. Bugni, Milwaukee, Wis., assignor to Square D Company, Park Ridge, Ill., a corporation of Michigan

Filed July 9, 1963, Ser. No. 75,718

Term of patent 14 years

(Cl. D10—8)

FIG. 1 is a front perspective view of a door handle showing my new design.

FIG. 2 is a front elevational view thereof.

FIG. 3 is a side elevational view thereof.

FIG. 4 is a rear elevational view thereof.

FIG. 5 is an enlarged fragmentary elevational view of a portion of the upper left corner of the handle in FIG. 2 showing a dotted portion within the upper square portion of the handle.

I claim:

The ornamental design for a door handle, substantially as shown.
